(57) **CLAIM**

The ornamental design for a turbine device, as shown and described.

DESCRIPTION

FIG. 1 is a perspective view of a turbine device showing my new design;

FIG. 2 is a top plan view thereof;

FIG. 3 is a bottom plan view thereof;

FIG. 4 is a side A elevation view thereof;

FIG. 5 is a side B elevation view thereof;

FIG. 6 is a side C elevation view thereof; and,

FIG. 7 is a side D elevation view thereof.

The broken lines in the drawing illustrate environmental structure and portions of the turbine device that forms no part of the claimed design.
